UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

SHUTTER.

Application filed May 3, 1920. Serial No. 378,375.

To all whom it may concern:

Be it known that I, RUDOLPH HOFFMAN, a citizen of the United States, residing at Kankakee, in the county of Kankakee and 5 State of Illinois, have invented certain new and useful Improvements in Shutters, of which the following is a specification.

The invention relates in general, to shutters, and more particularly contemplates the 10 provision of a shutter for closing the opening in the front wall of a kitchen cabinet or the like.

The general object of the invention is to provide a flexible shutter of advantageous 15 construction which is operable from a closed position over the opening into a collapsed position at one edge of the opening and vice versa.

A further object of the invention is to provide 20 a shutter of the character indicated comprising a series of hinged leaves mounted for relative pivotal movement so as to be capable of assuming either an extended or a collapsed relation, in which spring means are 25 provided for normally restraining such pivotal movement of the leaves.

The objects of the invention thus generally stated, together with other and ancillary advantages, are attained by the construction 30 and arrangement illustrated in the accompanying drawings forming part hereof in which Figure 1 is a perspective view of a kitchen cabinet equipped with a shutter which is constructed in accordance with my 35 invention. Fig. 2 is a vertical fragmentary sectional view of the rear side of the shutter showing the leaves in extended relation. Fig. 3 is a fragmentary vertical sectional view showing the leaves in end elevation and 40 illustrating the manner in which the leaves swing into compact relation. Fig. 4 is a similar view showing the leaves of the shutter extended. Fig. 5 is a view similar to Fig. 2 illustrating the action of the spring 45 means in the operation of folding the leaves from one position to another.

Referring now to Fig. 1 of the drawings, the invention is shown applied to a kitchen cabinet which may be of any preferred form 50 and is herein shown as comprising a base section 1, a top section 2, the base section being provided with the usual work table 3 and the top section having in its front wall a frame defining an opening 4 which is 55 adapted to be closed by a shutter indicated

generally by the numeral 5. The frame defining the opening 4 may comprise opposite side bars 6, a top bar 7 and a bottom bar 8.

The shutter comprises a plurality of leaves 9 hinged together so as to swing relative to each other, and one end of the shutter is pivotally secured at one edge (herein the upper edge) of the opening 4. Preferably the shutter is made of sheet metal, but any other suitable or preferred material may, of course, be employed.

The means for hingedly connecting the leaves together herein preferably comprises a plurality of hinge members 10 each comprising a rod 10^a mounted centrally of each leaf upon the rear side thereof so as to provide a central longitudinal axis for the leaf. At the opposite ends of said rod 10^a are provided arms or links 10^b extending in a generally rectangular direction from the rod 10^a and carrying at their ends laterally extending portions or studs 10^c which are pivotally mounted at the lower edges of the adjacent leaves. Preferably the studs 10^c are formed integral with a rod 10^d pivotally 80 mounted at the adjoining edge of the upper adjacent leaf, the rod extending throughout the length of each leaf and the lower edge of the leaf being beaded as at 11 so as to receive the rod. The means for pivotally 85 mounting the rod 10^a of the hinge member upon the leaves may consist of a plurality of cleats 12 suitably shaped to provide bearings for the rod. The hinge member of the upper end leaf, as shown in Fig. 2, is similar 90 to the hinge members of the other leaves except that the rod 10^d is omitted, the studs 10^c being mounted in suitable bearing members 13 upon the inner sides of the side portions 6 of the shutter frame and at the upper 95 end thereof. At the lower edge of the lowermost leaf the studs 10^c are provided upon the opposite ends of a rod 10^d, the portions 10^a and 10^b providing the hinge member being in this instance omitted. 100

The means for guiding the leaves in their movement from open to closed position and vice versa comprises guideways 14 provided at the opposite side edges of the opening 4. Herein said guideways are formed by an inwardly extending flange 15 bent up from the metal forming the side portions of the shutter frame 6, in spaced relation with reference to the inner side of said side portions 6. 110

Centrally of the rod 10^a of each of the hinge members is provided an upwardly extending member or hump 16 which normally lies flat against the inner side of the leaf. It 5 will be seen that said members 16 tend to restrain the pivotal movement of the leaves about their central longitudinal axes. Thus, as shown in Fig. 5, when a leaf is moved about its axis, the rod 10^a and the leaf are 10 forced apart by the member 16 so that both the rod and the leaf provide the spring action which is desired. The result is that the leaves are maintained in either their collapsed or extended relation by the spring 15 means until positively operated about their pivots in the movement of the shutter by the operator.

For facilitating the operation of the shutter it may be provided at its lower end 20 with suitable finger pieces or hooks 17. These hooks may be pivotally mounted upon the rod 10^a of the lower end leaf and arranged to overhang the lower portion 8 of the shutter frame, as shown in Fig. 4.

25 Any suitable means may be provided for supporting the leaves in their collapsed form such, for example, as a spring member or catch 18 which is automatically operable to operatively engage the leaves as they are 30 moved into their uppermost position. Said catch member may be secured at its upper end upon the upper portion 7 of the shutter frame 6, centrally thereof.

It will be seen that I have provided a 35 shutter which is of relatively simple construction and is capable of being easily operated either from an extended or closed position into a collapsed or open position, or vice versa. It is to be understood, however, that although the invention is herein 40 described with considerable particularity it is contemplated that various changes may be made without departing from the spirit and scope of the invention as expressed in 45 the following claims.

Claims to the shutter broadly, in combination with a kitchen cabinet, are contained in my copending application Serial No. 502,338, filing date September 22, 1921.

50 I claim as my invention:

1. A shutter comprising a series of hinged leaves for closing an opening in a wall, guideways provided at the sides of said opening with which the opposite edges of 55 the shutter are adapted to slidably engage to guide the leaves in their up and down movement, said leaves being mounted for pivotal movement with respect to each other so as to be foldable one upon the other into a compact stack, and spring means for resisting the pivotal movement of the leaves.

2. A shutter for closing an opening in a wall comprising a plurality of leaves, hinge devices for connecting said leaves together 65 for relative pivotal movement, each of said

devices providing a pivotal axis located approximately centrally of each leaf and extending longitudinally thereof, guide studs at one longitudinal edge of each of the leaves, guideways provided at the sides of 70 said opening for receiving and guiding said studs, and spring means tending to resist the relative pivotal movement of the leaves.

3. A shutter for an opening comprising a 75 plurality of leaves, hinge devices comprising a rod mounted approximately centrally of each leaf to provide a longitudinal axis therefor, means connecting said rods with one edge of an adjacent leaf, means for guiding the leaves for movement across said opening, and means normally resisting the relative pivotal movement of the leaves.

4. A shutter of the character described comprising a plurality of leaves, and hinge 85 devices for connecting the leaves together to permit of their operation into collapsed relation from an extended relation or vice versa, said devices comprising a link at each end of the leaf pivotally connected at one end with the leaf substantially upon its 90 central longitudinal axis and at its other end with the adjoining edge of an adjacent leaf.

5. A shutter of the character described 95 comprising a plurality of leaves, and hinge devices for connecting the leaves together to permit of their operation into collapsed relation from an extended relation or vice versa, said hinge devices comprising a longitudinally extending rod mounted centrally 100 of each leaf, an arm at the end of each rod extending in a direction substantially at right angles to the rod and having its free end pivotally connected with the adjoining edge of an adjacent leaf, said rod having means adapted to resist the pivotal movement 105 of its leaf upon the rod as an axis.

6. A shutter of the character described comprising a plurality of leaves, and hinge 110 devices for connecting the leaves together to permit of their operation into collapsed relation from an extended relation or vice versa, said devices each comprising an arm pivotally mounted at one end upon the central longitudinal of one leaf axis, and a rod 115 pivotally mounted upon the adjoining edge of an adjacent leaf and connected with the opposite end of said arm.

7. A shutter of the character described comprising a plurality of leaves, and hinge 120 devices for connecting the leaves together to permit of their operation into collapsed relation from an extended relation or vice versa, said devices comprising an arm pivotally mounted at each end of each leaf upon a central longitudinal axis, a rod pivotally mounted upon the adjoining edge of an adjacent leaf and connected with said arms, and spring means for normally resisting 125 relative pivotal movement of the leaves. 130

8. A shutter of the character described comprising a plurality of leaves, hinge devices adapted to connect the leaves together for relative pivotal movement, each of said devices having a pair of parallel members one of which is pivoted approximately on the central longitudinal axis of one leaf and the other of which is pivoted to the edge of an adjacent leaf, and a third member connecting said parallel members together.

9. A shutter of the character described comprising a plurality of leaves, hinge devices adapted to connect the leaves together for relative pivotal movement, each of said devices having a pair of parallel members one of which is pivoted approximately upon the central longitudinal axis of one leaf and the other of which is pivoted to the edge of an adjacent leaf, a third member connecting said parallel members together, and means for guiding the leaves from an ex-

tended edge to edge relation to a collapsed relation comprising a guideway and a stud rigid with the member connected to the edge of each leaf adapted to operate in said guideway.

10. A shutter for kitchen cabinets and the like comprising, in combination, a plurality of leaves, hinge devices for connecting said leaves together and each comprising a pair of parallel rods one of which is pivoted approximately midway between the edges of one leaf and the other end of which is pivoted to the adjoining edge of an adjacent leaf, arms connecting said rods at the opposite ends of each leaf, a stud rigid with the rod at the edge of each leaf, and means for receiving the stud to provide guideways therefor.

In testimony whereof, I have hereunto set my hand.

RUDOLPH HOFFMAN.
